CLOSURE OPERATOR

Rex A. Terry, Berkley, and Gustave C. Kuehn,
Huntington Woods, Mich., assignors to Chrysler
Corporation, Highland Park, Mich., a corpora-
tion of Delaware

Application November 19, 1948, Serial No. 60,924

7 Claims. (Cl. 160—188)

1

This invention relates to a closure operator particularly adapted for controlling the movement of folding, jackknife type, doors or the like.

In its preferred embodiment the invention will be described as applied to the side door opening of a short-haul or house-to-house delivery truck of the type shown in the co-pending application of R. Duff et al., Serial No. 47,213, filed September 1, 1948, but it will be understood that the closure operating mechanism and the other features herein disclosed are applicable to any foldable closure member.

While folding, jackknife type, side doors for motor vehicles are generally known and used, still, the mechanisms employed for controlling movement of these doors have been relatively complicated and quick to get out of order, have required the use of unsightly, laterally extending, guide plates around the edges of the door opening, and have not provided suitable guide means at both the upper and lower end edges of the doors so as to prevent binding between the doors and door jamb to thereby insure an easily operable door.

It is a primary object of this invention to provide a closure operating mechanism particularly adapted for jackknife type, folding doors which is simple and durable, eliminates the use of outwardly projecting guide plates along the edges of the door opening and provides positive guiding along both the upper and lower end edges of the doors so as to insure an easily operable, balanced, door movement.

It is a further object of this invention to provide a door actuating control link that also provides a guide track for the movable door sections.

It is another object of this invention to provide movable door guide mechanisms at both the upper and lower end edges of the folding doors which mechanisms are located entirely within the door jamb or vehicle body when the doors are closed and are arranged to be substantially unnoticeable when the doors are open.

It is an additional object of this invention to provide a door actuating mechanism that requires a minimum of manual effort and is so located that it is easily reached yet arranged such that it will not obstruct or interfere with passage through the door opening.

Additional objects and advantages of this invention will become apparent from a reading of the specification and a consideration of the related drawings wherein:

Fig. 1 is a plan view of the door guiding and actuating mechanism adapted to be mounted

5 along the top edge of a pair of jackknife folding doors, portions thereof being broken away and shown in section to more clearly disclose the invention. Solid lines show the doors in closed position whereas broken lines indicate the opened position of portions of the door sections and associated mechanism;

10 Fig. 2 is a fragmentary side elevation of the door actuation mechanism shown in Fig. 1 applied to a pair of folding, jackknife doors of a motor truck, the view being taken from within the truck looking towards the outside;

Fig. 2A is a fragmentary sectional elevational view taken on line 2A—2A of Fig. 2;

15 Fig. 3 is a side elevation of the door control mechanism adapted to be located along the bottom edge of the door, portions of the door and jamb being broken away and shown in section;

20 Fig. 4 is a sectional elevation of the door control mechanism shown in Fig. 3, the view being taken along the line 4—4 of Fig. 3. Solid lines represent the location of the doors and associated mechanism when in closed position and broken lines show the open positions of portions of the doors and control mechanism; and

25 Fig. 5 is a detailed sectional elevation of the pivot portion of the bell crank actuating means for the closure operator control link, the view being taken along the line 5—5 of Fig. 1.

30 Each set of folding doors 10 is designed to close a door opening, whose side edges are defined by the front and rear door posts 11 and 12 respectively and whose end edges are defined by the roof rail 13 and the truck floor 14. When the doors are in unfolded or closed position they are aligned with the outer side of the door jamb.

35 Each set of folding doors 10 comprises a front door section 15 and a rear door section 16 interconnected by a suitable hinge 17 which hinge extends the entire distance between the top and bottom of the doors at the adjoining side edge portions of each door section. Rear door section 16 is provided at its rear edge with a suitable hinge portion 18 which cooperates with a hinge portion 19 secured to the front side of the rear door post 12. Hinge portions 18 and 19 also extend the entire distance between the top and bottom edges of the doors. In this manner rear door section 16 is hinged to the body frame door post 12 while front door section 15 is hinged to and supported by its hinged mounting 17 on the rear door section 16.

40 Mounted on rear door section 16, adjacent hinge portion 18, and just below the top edge of door section 16 is a rigid offset toggle arm 21 which

has a portion projecting substantially normal to the inner surface of the door section 16. Arm 21 may be integral with a portion of door section 16 or may be welded or bolted thereto as desired. The free inwardly projecting end of arm 21 is provided with a vertically extending aperture adapted to receive a clevis pin 22. Pin 22 is pivotally connected to the bifurcated end of a control link yoke portion 23. The yoke portion 23 is fixedly mounted on the rearwardly extending end portion of control link 24. Linkage 21-24 constitutes a toggle mechanism adapted to effect door actuation.

Control link 24 is of inverted U or channeled-shaped cross section (see Fig. 5) and extends forwardly from arm 21 along the inner side of the door opening. Adjacent the front door post 11, control link 24 is provided with a vertically extending hollow boss member 25, which provides means for connecting control link 24 to its actuating mechanism.

Boss member 25 (see Fig. 5) has pivotally mounted therein a yoke member 26. The bifurcated end of yoke member 26 is pivotally connected by clevis pin 27 to the free end of lever arm 28 of bell crank 29. The other end of lever arm 28 has integrally formed therewith a transversely extending hollow boss portion 30, which boss portion is rotatably supported on a pivot stud 31 fixedly mounted in a U-shaped rigid support bracket 32 fixedly mounted on the vehicle body frame. Also connected to said boss portion 30 of bell crank 29 is a lever arm 33 which is adapted to be rotated about the pivot stud 31 so as to actuate the door control mechanism.

It will be noted from Fig. 2 that the arrangement herein provided locates the lever arm 33 in a position above the door along the body roof rail 13 where it may be conveniently grasped by a person desiring to operate the door control mechanism and, furthermore, the operating lever 33 is so positioned that it will not interfere with passage through the door opening. The lever arm 33 in both door opened and door closed positions is arranged to be located along the roof rail 13, as will be clearly pointed out in the subsequent description.

A bracket 44 having an offset arm portion 45 is secured by bolts 46 to the upper, forward, inner, surface portion of door section 15. Bracket arm 45 is provided with a vertically extending guide pin 47 adapted to have portions thereof movably mounted within the U-shaped channel or guideway of control link 24. Guide pin 47, which constitutes the follower means of the control link mechanism, has a circular bearing member 48 rotatably mounted thereon so as to provide a rolling connection between the guide pin 47 and the channel guideway of control link 24.

The control link 24 is a dual purpose element that transmits door actuating movement from the control lever 33 to the hingedly mounted door sections 15, 16 and at the same time link 24 provides a guide means for positively controlling movement of the foldable door sections. Control link 24 is located completely within the vehicle body when the doors are closed and when the doors are swung to open position only a small portion of the offset end of control link 24 is swung outside of the vehicle body (see Fig. 1). As a result of applicant's arrangement the conventional, outwardly projecting, stationary guideway structure for doors of this type has been eliminated and the general appearance of the vehicle improved due to the removal of unsightly, out-

wardly projecting guide plates from above the door opening.

To provide means for guiding the movement of the lower end edges of the folding doors and to balance the closure operating mechanism, a rigid, spring actuated, control link 51 is connected between the lower edge portion of the rear door section 16 and a slidably mounted cross head member 62 that is mounted beneath the floor 14 adjacent the forward portion of the door opening. Fixed to the lower end edge of rear door section 16 is a rigid, offset, lever arm 52 having a bifurcated free end portion which is pivotally connected by clevis pin 53 to the rearwardly extending end of lower control link 51. The forwardly extending end of control link 51 is pivotally connected to the cross head member 62 which member is adapted to slidably reciprocate in the guideway 63 that is fixedly mounted on the underside of the vehicle body floor 14. Adjustably mounted on the control link 51, intermediate its ends, is an anchor bracket 55 having an aperture 56 therein adapted to receive one end of a tension spring element 57. The opposite end of spring element 57 is anchored in an aperture 58 in the anchor bracket 59 mounted on the body frame adjacent the lower end of rear door post 12. Spring 57 is adapted to function as an actuating and overcenter device that assists in the movement of the door and is also adapted to hold the door in either its fully opened or fully closed position. By connecting the spring 57 and control link 51 to the lower edge of the door a balanced door operating mechanism is provided due to the fact that actuating, as well as guiding means, are located at both the upper and lower end edges of the door. Such an arrangement eliminates tilting, twisting, or cocking of the door sections and prevents binding between the door and surrounding door jamb during movement of the door between opened and closed position. This balanced control mechanism insures an easily operable door. It will be noted that the closure operating mechanism associated with the lower end edges of the door sections is arranged to be substantially completely enclosed by the cover plate housing 65. Housing 65 is detachably connected by bolts 66 to the under side of the floor 14 and to the associated body frame adjacent the door opening. Housing 65 prevents dirt, ice, or the like from accumulating on the contained closure operating mechanism 51-63 and thus a common source of interference with door movement is eliminated. When the door sections 15, 16 are moved to open position the offset pivotally connected ends of control link 51 and rigid arm 52 are swung outwardly through a slot 68 in the side wall 69 of housing unit 65. The offset pivotally connected ends of link 51 and arm 52 are the only portions of the lower closure operating mechanism visible when the doors are open and these portions of the operating mechanism are located adjacent the lower end of the rear door post 12 where they are practically unnoticeable and are out of the way so as not to interfere in any way with passage through the door opening.

The free side edge of forward door section 15 is provided with a resilient, tubular edge strip 71. Strip 71 is adapted to engage the front door post 11 when the doors are closed so as to provide a door sealing and cushioning element along the forward side edge of the door. A cantilever type sealing and cushioning strip 73 is also provided along the rear door post 12 to sealingly engage

the rear side edge of door section 16 when the door 19 is in closed position. Suitable sealing flaps or the like may also be provided along the upper and lower end edges of the door sections if desired.

Operation of this door control mechanism is as follows:

With the door in closed position, as shown in full lines in Figs. 1 and 4, the operator grasps the lever 33 and pulls downwardly to cause rotation of the lever 33 in a direction towards the front end of the truck. This forward rotation of lever 33 swings depending lever arm 23 forwardly and pulls control link 24 forwardly towards the front end of the truck. This forward movement of link 24 is transmitted through the offset toggle arm 21 to the hingedly mounted rear door section 16, causing rotation of rear door section 16 outwardly about the hinge pivot between hinge sections 18 and 19. After operating lever 33 has been rotated through an arc of approximately 45°, the door sections will have been swung about half open and control link 24 and the toggle linkage 21-23 will have reached its limiting forward position. However, momentum gained by the door sections during this initial door opening movement will carry the door sections 15, 16 over the toggle center after which the overcenter spring 57 will pull the door sections to their folded, rearwardly disposed, fully opened, positions. The fully opened position of the door sections 15, 16 are indicated in broken lines in Figs. 1 and 4. During the last half of the door opening movement the control link 24 is traveling rearwardly assisted by the pull of the overcenter spring 57, therefore physical effort is no longer required of the operator. During this latter portion of door opening movement the control lever 33 may be released for it will automatically return to approximately its initial position above the roof rail 13 where it will be out of the way so that it will not interfere with passage through the door opening. Spring 57 will retain lever 33 in its fully opened and fully closed positions along the roof rail 13.

During door opening movement rear door section 16 simply pivots outwardly about the hinge connections 18, 19 while the front door section 15 pivots about hinge 17. Front door section 15 is caused by the movement of guide pin 47 along the channeled guideway of control link 24 to swing outwardly and fold upon to the inner side of rear door section 16 at a location rearwardly of the rear door post 12.

When it is desired to close the door, operating lever 33 is again pulled downwardly and thereby rotated forwardly about pivot pin 34 which movement causes lever arm 23 to swing the control link 24 and door sections 15, 16 forwardly about the hinge connections 18, 19 and effect an unfolding motion exactly opposite to that occurring during door opening movement. The movement of the door sections during closing movement is also positively guided by the aforementioned guide mechanism that is located at the upper and lower end edges of the door unit 10.

As a result of the door control guideway mechanism provided by follower 47 and U-shaped control link 24 at the upper end edges of the door unit and by the spring controlled arm and link mechanism 51, 52, 57, 62, 63 at the lower end edges of the door unit, binding of the door is prevented. Due to the door closure mechanism herein disclosed providing suitable control means at both the upper and lower end edges of the door sections an easily operable, balanced, closure

mechanism has been provided. Furthermore, the novel control structure for the upper edges of the door eliminates certain guide parts heretofore required due to the control link 24 serving the dual function of an actuating member as well as guiding member for the movable door sections. Also it will be noted that the control means at both ends of the door are completely shielded from the elements when the door is closed so that their operation cannot be impaired by the accumulation of ice, dirt or the like.

We claim:

1. In a motor vehicle, a body having a door opening and a door therefor comprising a plurality of foldably connected sections, one of said sections being hingedly mounted on said body at one side edge of the door opening, a bell crank control lever pivotally mounted within said body adjacent the upper end of the door opening, a first rigid arm projecting from the upper end portion of the door section hingedly mounted on said body, a rigid, control link extending along the upper end edge of the door opening and pivotally connected at its opposite ends to said control lever and said first rigid arm, said control link having a guideway extending lengthwise thereof, a guide pin carried by the upper end portion of another of said door sections having parts thereof mounted for movement along the guideway in said control link, a second rigid arm projecting from the lower end of the door section that is hingedly mounted on the body, and spring actuated, overcenter linkage connected between said second rigid arm and a guideway mounted on the body adapted to actuate and guide the movement of the lower end of said one of the door sections and providing means to retain the door sections in fully opened and fully closed positions, said overcenter linkage at the lower end of the door cooperating with the guiding and actuating linkage at the upper end of the door to provide a pair of opposite disposed door actuating and guiding linkages that prevent binding of the door sections during actuation thereof.
2. A closure operator for a foldable, multiple section, closure member that is adapted to be folded and unfolded across an opening, said closure member including an end folding section that is adapted to be hingedly mounted along one side of the opening and at least one other folding section that is pivotally connected to the said end section comprising a control lever for the closure operator that is adapted to be movably mounted relative to said closure member, a rigid closure member actuating and guide link adapted to extend along one edge of the opening, means pivotally connecting opposite end portions of the said link to the control lever and to the end section of the closure member respectively, a trackway carried by said link and arranged to extend lengthwise thereof, follower means carried by the said other section of the closure member having portions thereof connected with said trackway for guided movement relative thereto during movement of said closure member between folded and unfolded positions relative to said opening, said link and follower means providing means for both actuating and guiding the movement of said closure member.
3. In combination, a body having a door opening therein and a door closure therefor comprising a plurality of foldably connected door sections, one of said sections being hingedly mounted on said body at one side edge of the door opening, a control lever pivotally mounted

7 on the body adjacent one end edge of the door opening, a rigid arm mounted on and projecting from an end portion of the door section that is hingedly mounted on the body, a rigid, control link extending along said aforementioned one end edge of the door opening, said control link being pivotally connected at its opposite ends to said control lever and said rigid arm respectively, said control link being formed with a guideway extending lengthwise thereof, and a guide pin carried by the end portion of another of said door sections having portions thereof mounted within the guideway in said control link for movement therealong, the arrangement of the control link and guide pin being such that actuation thereof automatically effects guided relative movement between the several door sections.

4. In a motor vehicle body having a door opening therein including vertically extending front and rear door posts, a folding sectional door for said opening comprising a pair of hingedly connected door sections one of which is hingedly mounted on one of said door posts for pivotal movement about a vertical axis, a roof rail member rigid with the body bridging said posts and defining the upper edge of said door opening, a bell crank lever pivotally mounted on said body for rotation in a vertically extending plane, said lever comprising an operating handle normally extending in a substantially horizontal direction along said roof rail member and a depending crank arm normally extending in a substantially vertical direction, an offset arm carried by the door section that is hingedly mounted on one of said door posts, a rigid control link pivotally connected to and extending between the lever crank arm and the offset arm, said control link including a trackway that extends lengthwise of the link, and follower means mounted on the other door section having portions thereof mounted on said link trackway for travel along said trackway, said link trackway and follower means cooperating to guide the movement of the door sections during actuation thereof.

5. A body having a door opening therein and a door closure therefor comprising a plurality of foldably connected sections, one of said sections being hingedly mounted on said body at one side edge of the door opening, a control lever pivotally mounted within said body, an offset arm projecting from an end portion of the door section that is hingedly mounted on said body, a movable combination door actuating and guide link extending along one end edge of said door opening and pivotally connected at its opposite ends to said control lever and said arm respectively, said control link having a guideway formed therein extending lengthwise of the link, and follower

means carried by another of said door sections having portions thereof mounted within the guideway in said control link for travel therealong during movement of the door sections, 5 actuation of said link effecting guided movement of the several door sections between door opened and closed positions.

6. In a door opening and closing device, the combination with a folding sectional door comprising a plurality of hingedly connected sections one of which is pivotally mounted on a support, of an arm connected to and projecting from said one of the door sections, an operating lever mounted for movement relative to said door sections, 10 a combination actuating and door guiding link pivotally connected between said arm and said operating lever, said link mounting a guideway that extends longitudinally along the link, and a follower carried by another of said door sections and having portions thereof engaged with said guideway so as to travel along said guideway during movement of the door sections, actuation of said operating lever effecting relative movement between said sections and guiding the movement of the last mentioned door section.

7. In a motor vehicle, a body having a door opening and a door therefor comprising a plurality of hinged together sections one of which is hingedly connected to the vehicle body along its 15 free side edge so as to permit said sections to be foldable into side-by-side relation beside said door opening, an offset arm carried by the door section hingedly connected to the vehicle body, an operating lever mounted on said body for movement thereto, a combination door actuating and door guiding link connected between said swing arm and said operating lever, said link including a guideway formation, and a follower means carried by another of said door sections 20 having portions thereof mounted within said control link guideway for travel therealong during door movement, actuation of said link and follower means effecting guided movement of each of said door sections.

45 REX A. TERRY.
GUSTAVE C. KUEHN.
